Primary Examiner — Darlington Ly(74) *Attorney, Agent, or Firm* — Briggs and Morgan, P.A.; Gerald E. Helget(57) **CLAIM**

The ornamental design for a 4-in-1 multiple socket driver, as shown and described.

DESCRIPTION

FIG. 1 is a front perspective view showing my new design for a 4-in-1 multiple socket driver;

FIG. 2 is a top plan view;

FIG. 3 is a left side elevational view which is a mirror image of the right side elevational view;

FIG. 4 is a bottom plan view;

FIG. 5 is a rear elevational view;

FIG. 6 is a front elevational view;

FIG. 7 is a left side elevational view with the front end of the inner hexagonal shaft extended forwardly; and,

FIG. 8 is a left side elevational view with the rear end of the inner hexagonal shaft extended rearwardly.

The broken lines in the drawings illustrate the inner shaft portion of the 4-in-1 multiple socket driver to which forms no part of the claimed design.

1 Claim, 2 Drawing Sheets(56)
